UNITED STATES PATENT OFFICE.

WILLIAM B. GREER, OF WHEELING, WEST VIRGINIA.

ORCHARD-HEATER.

1,112,902.

Specification of Letters Patent.

Patented Oct. 6, 1914.

Application filed June 16, 1914. Serial No. 845,427.

To all whom it may concern:

Be it known that I, WILLIAM B. GREER, a citizen of the United States of America, and resident of Wheeling, county of Ohio, and 5 State of West Virginia, have invented certain new and useful Improvements in Orchard-Heaters, of which the following is a specification.

This invention relates to orchard heaters, 10 and it has for its primary object to provide a simple and efficient heater of the oil-burning type having means whereby the rate of combustion may be regulated and, consequently, whereby the heat radiation may be 15 controlled.

A further object is to provide a device of the character mentioned which is devoid of complication, which is comparatively inexpensive to manufacture and which is designed to produce combustion of a highly 20 efficient character.

In describing the invention in detail, reference is herein had to the accompanying drawings, forming a part of this specification, in which—

Figure 1 is a view partly in side elevation and partly in vertical section; Fig. 2 is a partial section on the line 2—2, Fig. 1; and Fig. 3 is an enlarged detail section on the 30 line 3—3, Fig. 2.

Referring to said drawings, in which like designating characters distinguish like parts throughout the several views—1 indicates a receptacle or container for liquid fuel, said 35 container being circular in form and preferably composed of sheet metal. Located at a point adjacent to the upper end of said container is an annular inwardly directed crimp or bead 2 which constitutes a seat for the 40 lower end of a low frusto-conical shield or false cover 3 which is open at both ends, as shown. Located at a point above the crimp or bead 2 is an outwardly directed annular crimp or bead 4 which constitutes a seat for the 45 inner edge of the horizontal portion of a close-fitting ring 5 which embraces the upright flange-like upper end 6 of the container. Said ring is substantially L-shaped in cross-section, having an upright flange 50 at the outer edge of said horizontal portion. Fitted closely to the said flange of said ring is the annular flange-like rim 7 of an upwardly tapered cover 8 having a central opening or passage 9 therethrough for permitting egress to a superposed stack 10 of the products of combustion arising from the

container through the upper end of the shield 3. Seated upon the horizontal portion of said ring 5 is a circular ring 11 which is adapted to be rotated slightly for moving a plurality of perforations or apertures 12 provided therein into and out of registration with similar perforations or apertures 13 provided in the said horizontal portion of ring 5, said perforations or apertures being designed, when in register, to admit air which thence passes upward between the cover 8 and the shield 3 for mixing with the gases issuing through the top of the latter for facilitating combustion of 70 said gases within said stack.

Provided in the horizontal portion of the ring 5 is one or more short slots 14 through which project studs or pins 15 which are fixed in the ring 11, said studs or pins 75 affording exposed means whereby said ring 11 may be engaged for effecting its rotation, and said slots serving to limit the extent of rotation. As is obvious, any desired degree of registration between the apertures 12 80 and 13 may be effected, and, as a consequence, the amount of air admitted may be regulated. Thus, means is afforded whereby the rapidity of consumption of the fuel may be accurately regulated for producing 85 the desired amount of heat generation.

As is obvious, the shield 3 may be more or less inclined with respect to the cover 8, or may be entirely dispensed with. However, it has been found in practice that slightly 90 better combustion is accomplished when said shield is used, the air admitted being thereby directed upward to a point where it mingles with the gases at a point near the base of the stack.

While the seats for the shield 3 and the ring 5 are herein shown as afforded by the reversely disposed annular bead-like crimps 2 and 4, it will be apparent that this particular form of seats is not essential.

What is claimed is—

1. An orchard heater comprising a circular container, an external annular seat formed on said container adjacent to its upper end, an apertured ring mounted on said seat, a second apertured ring adjustably mounted on the first mentioned ring, a tapered cover having a central opening therein mounted over said container, said cover having a rim in engagement with one of said rings, and a stack mounted on said cover about said opening.

2. An orchard heater comprising a circular container, an external annular seat formed on said container adjacent to its upper end, an apertured ring mounted on 5 said seat, a second apertured ring adjustably mounted on the first mentioned ring, a tapered cover having a central opening therein mounted over said container, said cover being seated upon one of said rings, 10 and a stack mounted on said cover about said opening.

3. An orchard heater comprising a circular container, an external annular seat formed on said container adjacent to its 15 upper end, an apertured ring mounted on said seat, a second apertured ring adjustably mounted on the first mentioned ring, a tapered cover having a central opening therein mounted over said container, said 20 cover being seated upon one of said rings, a stack mounted on said cover about said opening, and an upwardly tapered shield having its lower end seated within and adjacent to the top of said container, said 25 shield being open at both ends.

4. An orchard heater comprising a circular container, an external annular seat formed on said container adjacent to its upper end, an apertured ring mounted on 30 said seat, a second apertured ring adjustably mounted on the first mentioned ring, a tapered cover having a central opening therein mounted over said container, said 35 cover being seated upon one of said rings, a stack mounted on said cover about said opening, and an upwardly tapered shield having its lower end seated within and adjacent to the top of said container, said 40 shield being open at both ends and terminating at its upper end adjacent to the opening in the cover.

5. An orchard heater comprising a circular container, an external annular seat formed on said container adjacent to its 45 upper end, a ring mounted on said seat, said ring having a horizontal apertured portion, a second ring adjustably mounted on the first mentioned ring and having apertures for registration with those of the latter, a 50 cover having an annular rim seated upon one of said rings outside said apertures, said cover having an opening therein, and a stack mounted on said cover about said opening.

6. An orchard heater comprising a circu-

lar container, an external annular seat 55 formed on said container adjacent to its upper end, a ring mounted on said seat, said ring having a horizontal apertured portion, a second ring adjustably mounted on the first mentioned ring and having apertures 60 for registration with those of the latter, a cover having an annular rim seated upon and having a portion embracing the first mentioned ring, said cover having a central opening therein, and a stack mounted on 65 said cover about said opening.

7. An orchard heater comprising a circular container, an external annular seat formed on said container adjacent to its upper end, a ring mounted on said seat, said ring 70 having a horizontal apertured portion, a second ring adjustably mounted on the first mentioned ring and having apertures for registration with those of the latter, a cover having an annular rim seated upon one of said rings 75 outside said apertures, said cover having an opening therein, a stack mounted on said cover about said opening, and an upwardly tapered shield disposed below said cover and having its lower end seated upon said 80 container, said shield opening outward at its upper end adjacent to the opening in the cover.

8. An orchard heater comprising a circular container, an external annular seat 85 formed on said container adjacent to its upper end, a ring mounted on said seat, said ring having a horizontal apertured portion, a second ring adjustably mounted on the first mentioned ring and having apertures for 90 registration with those of the latter, a cover having an annular rim seated upon one of said rings outside said apertures, said cover having an opening therein, a stack mounted on said cover about said opening, an internal 95 annular seat formed on said container adjacent to its upper end, and an upwardly tapered shield having its lower end resting on said internal seat, said shield opening outward at its upper end adjacent to the opening in the cover.

In testimony whereof, I affix my signature in presence of two subscribing witnesses.

WILLIAM B. GREER.
